UNITED STATES PATENT OFFICE.

PAUL VON KIRÁLY AND JOSEF LOVÁSZ, OF BUDAPEST, AUSTRIA-HUNGARY.

AUTOMATIC BREECH-LOADING FIREARM.

1,073,908.

Specification of Letters Patent. Patented Sept. 23, 1913

Application filed November 21, 1912. Serial No. 732,643.

To all whom it may concern:

Be it known that we, PAUL VON KIRÁLY and JOSEF LOVÁSZ, subjects of the King of Hungary, residing at Budapest, Austria-Hungary, have invented certain new and useful Improvements in Automatic Breech-Loading Firearms, of which the following is a specification.

In automatic firearms especially of that class in which there is no positive locking action and if constructed for firing cartridges of strong power, it is necessary to provide a very heavy and comparatively large breech piece, in order to save the cartridge bottoms from tearing off and also to avoid any violent rearward motion of the breech block which becomes frequently dangerous. Furthermore the fact that the breech block is normally of considerable mass and high inertia reduces materially the recoil of automatic fire arms of the positive locking type.

The object of the present invention is to improve the breech mechanism of automatic fire arms so that it will be adapted to afford a relatively great inertia yet having a comparatively low weight and small compass.

In the accompanying drawings the breech mechanism is illustrated as an example of the invention, no positive locking means being provided in that case.

Figure 1 is a longitudinal section horizontally taken through the breech casing, where the breech block is shown in closed position; Fig. 2 is a similar section of the breech casing, the breech block being shown in partly closed section; Figs. 3 and 4 are cross-sections along lines A—C and B—D of Fig. 1.

The firing mechanism, the reaction or closing spring, the magazine, etc., are not parts of the invention and can be formed in a different manner. The parts are not represented in the drawings.

The breech block consists of two parts, the inner part m_1 and the outer part m in connection with each other by the double-armed lever l . This lever l is pivoted in the outer part m by means of the pin x and engages with the inner part m_1 by means of its projection n . By oscillating the lever l rearwardly the inner part m_1 is correspondingly retracted within the outer part m . The movement of the lever l and therefore the movement of the inner breech part m_1 is limited by the lever l with its right side abutting the back-edge of the lateral

recess of the breech mechanism, while the inner part m_1 borders the left side of the lever l (see Fig. 2).

The two arms of the lever l are of different length and that in a ratio of about 1: up to 1:6. When the breech mechanism is closed, the lower arm n_1 of the lever l is supported on the front part of the lever l , which latter is pivotally mounted on a pin y in a side recess of the casing c and which is held in an upright position by the small spring s . Now the lower projection or arm n_1 of the lever l in the first period of the rearward motion of the breech block abuts against this lever a . Consequently, the lever l will be swung rearwardly and simultaneously the inner part m_1 is thrown rearwardly with a velocity that is greater than the velocity of the outer part in the ratio of the lengths of the two arms of the lever l . Therefore the inner part offers so great resistance against the rearward motion as its mass or weight would be greater than is really. The greater the ratio of gear or leverage of the two arms of lever l , the greater is consequently the inertia of the breech block. For that reason the breech block is to be divided in such a manner that the inner part m_1 is heavier than the outer part.

In the position according to Fig. 2 the rearward motion of the inner part m_1 in the outer part m is completed. The two parts may be locked in this position, until the breech mechanism has reached its initial position represented in Fig. 1. Now the inner part m_1 may be released whereupon it returns to its initial position under the influence of a spring k suitably mounted.

During the return movement of the breech mechanism the lever a is swung forward by means of the lower arm n_1 of the lever l , thus it goes out of the path of this lower arm and the breech block can freely continue its forward stroke.

In applying this invention to automatic fire arms with positive locking action the breech mechanism is arranged in the same manner irrespective of the locking mechanism which is independent of the present invention.

Having thus described our said invention what we claim as new and desire to secure by Letters Patent is:—

In an automatic firearm with a breech block consisting of an outer and an inner

rt the combination of a two-armed lever
a connective member for the said parts,
e arms being of different length and the
nger arm engaging with the inner part,
ile the short arm, pivoted in the outer
rt projects therefrom, and a stop pivoted
the casing and adapted to engage said
ort arm and throw the long arm backward
the opening movement, and to yield and

permit said short arm to pass in the closing 10
movement, of the breech block.

In testimony whereof we have affixed our
signatures in presence of two witnesses.

PAUL VON KIRÁLY.
JOSEF LOVÁSZ.
